UNITED STATES PATENT OFFICE.

PETER D. HOLDEN, OF ROXBOROUGH, PENNSYLVANIA.

NUT-LOCK.

1,184,646.

Specification of Letters Patent.

Patented May 23, 1916.

Application filed February 17, 1915. Serial No. 8,820.

To all whom it may concern:

Be it known that I, PETER D. HOLDEN, a citizen of the United States, residing at 505 East Seville street, Roxborough, in the 5 county of Philadelphia and State of Pennsylvania, have invented new and useful Improvements in Nut-Locks, of which the following is a specification.

The present invention relates to improvements in means for locking a nut upon a bolt, 10 and the object of the invention is to provide a device of this character which is simple in construction, cheap to manufacture and which will perform its function with 15 ease and accuracy.

With the above and other objects in view, the improvement resides in the construction, combination and arrangement of parts set forth in the following specification and 20 falling within the scope of the appended claim.

In the drawings: Figure 1 is a sectional view illustrating the application of my improvement, Fig. 2 is an end view of the 25 same, Fig. 3 is a sectional view approximately on the line 3—3 of Fig. 2, Fig. 4 is a view similar to that illustrated in Fig. 2 but showing the application of the locking elements before the nut or bolt is turned to 30 bring the locking member into engaging position, Fig. 5 is a detail perspective view of the bolt, Fig. 6 is a similar view of the nut, Fig. 7 is a similar view of the locking member, Fig. 8 is an elevation, partly in 35 section, illustrating a modification, and Fig. 9 is a side view of a device as disclosed in Fig. 8.

Referring now to the drawings in detail, 1—1 designate two plates which are adapted 40 to be connected by a bolt 2 and a nut 3. The bolt 2 is of the ordinary construction, except that the end of its shank, opposite that of its head is provided with a square or rectangular portion 4, and the corners of 45 said portion 4 are threaded, as at 5.

The numeral 6 designates a washer which is adapted to be arranged upon one of the plates 1 between the said plate and the nut. The nut 3 has its outer face formed adjacent 50 two of its opposite edges with longitudinally extending lugs 6'—6' which are

arranged in parallelism and which preferably have their inner faces depressed to provide angular walls 7.

The numeral 8 designates what I term the 55 locking element for the device, the same comprising a substantially rectangular or square plate having two of its opposite edges beveled, as at 9—9, and the said beveled edges are adapted to be received within the recess 60 or beveled edges provided by the members 6'—6' of the nut 3.

It is to be understood that the member 8 is of a less width, between its beveled edges, than that of the face of the nut between 65 its projections 6'—6', so that when the nut is screwed home upon the bolt, the member 8, which is provided with a rectangular or square bore 10 may be arranged over the extension 4 of the bolt and may 70 have its beveled sides or edges arranged adjacent the beveled sides 7 of the members 6'. A retrograde movement of the nut or bolt as illustrated in Fig. 2 will force the sides 9 of the member 8, the bore 10 75 of which snugly engages with the extension 4 of the said bolt, so that the said beveled edges 9 will contact with the beveled walls provided by the members 6', and so prevent a retrograde or unscrewing movement of the 80 nut or bolt.

In Figs. 8 and 9 the locking member 10' is provided at its diametrically opposite corners with shoulders 12—12 which are adapted to be received within angular depressions or pockets 13—13 formed in enlarged or thickened portions 14—14 upon the diametrically opposite corners of the nut 15, the bolt 16 being provided with a rectangular opening 17 to receive the rectangular bore 18 of the member 10.

Having thus described the invention, what I claim is:

The herein described construction of means for locking a nut upon a bolt including a bolt having its shank provided with a rectangular extension, the corners of which are threaded, a nut for the bolt, said nut having its outer face in a line with two of its sides formed with projections, the inner 95 adjacent walls of which being angular to provide pockets, a rectangular plate having 100

two of its opposite edges beveled and of a size to be received between the projections of the nut, said plate having a rectangular opening to receive the rectangular extension of the bolt and adapted to be arranged against the outer face of the nut and to have its beveled edges partly received in the pockets of the projections when the nut is

turned upon the bolt in an unscrewing direction.

In testimony whereof I affix my signature in presence of two witnesses.

PETER D. HOLDEN.

Witnesses:

JOHN E. JONES,
CHARLES J. RUMSEY.
